D. W. RUSSELL

SHADE OR CURTAIN HOLDING FIXTURE

Filed Dec. 31, 1917

Inventor:
Donald W. Russell
By J. L. Shaeffer
Attest

UNITED STATES PATENT OFFICE.

DONALD W. RUSSELL, OF JEFFERSON, IOWA.

SHADE OR CURTAIN HOLDING FIXTURE.

Application filed December 31, 1917. Serial No. 209,768.

To all whom it may concern:

Be it known that I, DONALD W. RUSSELL, citizen of the United States of America, and resident of Jefferson, Greene County, 5 Iowa, have invented a new and useful Shade or Curtain Holding Fixture, of which the following is a specification.

An object of this invention is to provide improved means for supporting a shade 10 roller or curtain rod while the same is being raised or lowered.

My invention consists in the construction, arrangement and combination of elements hereinafter set forth, pointed out in my 15 claim and illustrated by the accompanying drawing, in which—

Figure 1 is a front elevation and Figure 2 a side elevation showing my improved devices mounted as required for practical 20 use. Figure 3 is a cross-section on the indicated line 3—3 of Figure 1. Figures 4 and 5 are plan views, on an enlarged scale, of clips and pulleys employed in the device, cables being shown thereon. Figures 6 and 25 7 are detail rear and end elevations respectively of a winding drum, housing and cable employed in the device, shown on an enlarged scale.

In the construction and mounting of the 30 device as shown the numerals 10, 11 designate the interior face casings and 12 the interior head casing of a window frame, the same being shown conventionally. Square-arched guides 13, 14 are mounted in parallel 35 upright positions on and are secured at their ends to the face casings 10, 11 and the body portions of said guides are parallel with and spaced from the faces of said casings. A hanger, composed of flat metal bars 40 15, 15^a, one of which is formed throughout a portion of its length with turned edges forming guideways in which the other bar is received whereby said bars are adapted to be mounted in longitudinally-sliding relation with each other, is provided and eyes 45 16, 16^a are mounted in outer end portions of said bars and embrace and are adapted to slide on the body portions of the guides 13, 14. Ears 17, 17^a are formed on and ex- 50 tend laterally from the outer ends of the bars 15, 15^a and said ears are formed, respectively, with a means for supporting one end of a curtain rod or shade roller (not shown); such means in this instance being 55 represented by a notch 18 in the ear 17 adapted to receive one end member of a

shade roller of common form, the other ear being formed with a round hole (not shown) in a common manner. Cables 19, 19^a are attached to the bars 15, 15^a adjacent the 60 eyes 16, 16^a and extend upwardly therefrom around pulleys 20, 20^a mounted on the head casing 12. The cable 19^a extends along the front of the head casing 12 and around a pulley 20^b. The pulley 20^a is 65 pivoted in a clip 21 fixed to the head casing 12 and the pulleys 20 and 20^b are pivoted side by side in a clip 21^a, of greater length than the clip 21, also fixed to said head casing. The pulley 20^b is of slightly greater 70 diameter than the pulley 20 and the pulley 20^b and its clip may be set at a slightly greater altitude than the clip 21^a to permit the cable 19^a to extend across the cable 19 without contact therewith. The cables 19, 75 19^a extend downwardly along the front face of the casing 10 side by side and are attached to and adapted to be wound on a drum 22 pivoted in a housing 23 fixed to the outer face of the lower end portion of 80 the casing 10. The cables 19, 19^a may be separate or may be portions of a single cable having its intermediate portion engaged by a pin 22^a projecting radially from the drum 22 within the housing 23. The 85 drum 22 is formed with a crank 22^b on one end and also is adapted for reciprocation in its seats in the ends of the housing. The drum 22 also is formed with a pin 22^c outside of and adjacent to an end 23^a of the 90 housing 23, which pin is adapted to engage at times with an inclined lug 23^b formed in and struck out from said end 23^a. An expansive coil spring 24 is mounted on the drum 22 and impinges at opposite ends in 95 the inner face of the end 23^a of the housing and a pin 22^d mounted in and projecting from said drum and spaced from said end. It is the function of the spring 24 to press the drum 22 longitudinally and, normally, hold the pin 22^c in the plane of the inclined lug 23^b, thereby preventing accidental unwinding of the cables from the drum.

In practical use a shade roller, or other device, may be mounted on the ears 17, 17^a 105 of the hanger and be raised and lowered with said hanger by manipulation of the drum. During the operation of winding the cables to raise the hanger and device carried thereby the drum is manipulated so 110 that the pin 22^c rides over the inclined lug 23^b and is in position to be engaged and

stopped by said lug whenever manual force is relaxed and the cables tend to unwind from the drum because of the weight of the hanger. During the operation of unwinding the cables to lower the hanger, the drum is moved longitudinally by hand against the pressure of the spring 24 so as to permit the pin 22^a to pass freely over the inclined lug 23^a.

10 I do not desire to be understood as limiting myself to the construction and arrangement of parts as shown and described, as the same may be modified without departing from my invention.

15 I claim as my invention—

A shade or curtain holding fixture comprising flat metal bars, one of which is

formed throughout a portion of its length with turned edges forming guideways in which the other bar is received whereby 20 said bars are adapted to be mounted in longitudinally-sliding relation with each other, the outermost end portions of said bars extending laterally and forming integral ears, said ears being formed with means 25 for supporting a shade-roller, and eyes fixed to the respective bars adjacent to and between said ears, said eyes having their openings in the same horizontal plane and adapted to receive and have sliding engagement with suitable guides.

Signed by me at Des Moines, Iowa, this fifteenth day of December, 1916.

DONALD W. RUSSELL.
